TELEGRAPH CIRCUIT MONITORING DEVICE

Harold O. Peterson, Riverhead, N. Y., assignor to
Radio Corporation of America, a corporation of
Delaware

Application January 28, 1938, Serial No. 187,353

9 Claims. (Cl. 178—69)

This invention relates to monitoring devices and more particularly to an arrangement for indicating abnormal conditions in a telegraph circuit or radio communications channel so that when the signal departs from prescribed operating limits an indication will be made or an alarm will be sounded.

It is an object of my invention to provide a monitoring device for a telegraph circuit such that when the so-called "marking" elements of the received signals are compared with the spacing elements thereof in integrated time duration value and the relationship is found to be abnormal, an alarm or other indicating device may be actuated.

This invention is primarily applicable to radio telegraph circuits but may, in some instances, be applied to circuits carrying other forms of communications. In telegraph circuits, the signal is keyed in accordance with a telegraph code so that the signal consists of dots and dashes separated by spaces. In this specification the term "mark" is used to designate the dots and dashes and the term "space" to designate the spaces between dots and dashes. It is general experience that in the handling of such communications the summation of all the dots and dashes is about equal to the summation of all the spaces. In other words, under normal operating conditions the signal is on mark about 50% of the time. Now if serious interference occurs, some of the space intervals will contain energy and the summation of mark will be abnormally high. If, on the other hand, the circuit is suffering from drop-outs or fading the summation of mark will be abnormally low. It is the purpose of the device herein described to detect and register when these abnormal conditions exist.

My invention will now be described in detail, reference being made to the accompanying drawing in which:

Figure 1 shows a circuit suitable for registering an abnormality in the telegraph line or radio channel whenever the percentage of "mark" is abnormally low, and

Fig. 2 shows a modification of the invention in which the alarm or other indicating device is adapted to respond whenever the percentage of "mark" is either too high or too low.

As will be seen from the description to follow, the devices shown in the two embodiments herein illustratively presented are sensitive to the percentage of "mark" measured in time, and the circuits are designed to be quite independent of normal variations in the signal amplitude.

Referring to Fig. 1, electronic device or tube 8 is normally biased to cut-off by the D. C. drop in resistor 5. When the signal fed through transformer 4 is on mark, tube 8 will draw plate current through resistor 2 and will place a charge on condenser 10 such that the grid of electronic tube 9 is biased negative past cut-off. Condenser 10 charges very quickly but discharges quite slowly. By proper choice of constants assigned to condenser 10 and resistor 2, the time required for discharge may be made a value suitable to fit the requirements. This time constant is ordinarily adjusted so that the normal space intervals are not long enough to allow appreciable discharge of the voltage across condenser 10. For this condition of regular and prescribed percentage mark, electronic tube 9 will remain biased to cut-off and zero plate current will flow through relay 11. If, however, the signal ceases to mark for a predetermined interval, condenser 10 will discharge through resistor 2 and the grid potential of electronic device 9 will assume such a value that current will flow through relay 11 closing the contact thereof which, in turn, causes current to flow through the coil of relay 12. When current flows through the coil of relay 12 its contacts cause current to flow through indicating lamp 16, alarm device 14 and the coil of special relay 13. The current to the alarm device 14 passes through the contacts of relay 13. Relay 13 may be provided with a dash pot or other delay action so that after a few moments the circuit to alarm 14 is broken, to be restored periodically after predetermined intervals of time as long as energy is supplied through the contacts of relay 12.

Referring to Fig. 2, electronic device or tube 32 is normally biased to cut-off by the D. C. voltage drop in resistor 17. The resistor 17 forms part 40 of a potentiometer having other portions designated 18 to 25 inclusive. This potentiometer may be suitably polarized by means of a direct current source the positive terminal of which is connected to the outer end of the resistor 25 preferably through a choke coil 26. The outer end of the resistor 17 is connected to the negative terminal of the direct current source and may, if desired, be grounded. A capacitor 27 connected between the resistor 25 and choke 26 is of large value, and, being grounded to the other side, serves in combination with the choke 26 for smoothing out any ripple component, if any, which may be present in the D. C. source.

When the signal is on mark, tube 32 draws plate current through resistor 43 and charges

condenser 44 in such manner that electronic device 35 is biased to cut-off. This cut-off bias reduces the direct current potential drop in resistor 46 to practically zero and consequently electronic device 36 will draw plate current through resistor 49 thereby placing a negative bias on condenser 50 through resistor 48. It can be arranged so that appreciable time will be required to establish this negative potential on condenser 50 by adjustment of its capacitive value and of the value of resistor 48. This negative potential is such that, for normal percentage mark, the contacts of relay 51 remain open. If now the percentage mark becomes abnormally low, electronic device 36 draws current a correspondingly lower percentage of the total elapsed time and consequently the average potential established on the grid of electronic device 31 will be less negative and more current will flow through the coil of relay 51 causing its contacts to be closed and an indicator or alarm device 62 connected thereto will be operated.

In the same circuit, when the signal is on mark, electronic device 32 draws current through resistor 43 causing electronic device 35 to be biased to cut-off with correspondingly small D. C. drop in resistor 46. This condition of small drop in resistor 46 causes the grid of electronic device 53 to assume a potential which will cause plate current to flow through relay 52 and operate its associated indicating or alarm device 63. A time delay action is provided in the form of resistor 15 and condenser 54.

The discharge tubes 37 and 53 are collaterally disposed in the final stage of the cascaded network. These two tubes, however, are rendered conductive at mutually exclusive times due to the different preceding stages by which their grids are controlled.

It should be noted that for the condition of mark the drop in resistors 49 and 46 is quite independent of input signal strength. Also for the condition of space the D. C. potential drops in these two resistors are substantially independent of signal strength during the mark interval. By virtue of this keying action, time constant circuits 48-50 and 15-54 are substantially time-integrating devices so arranged that relay 51 will be caused to close its contacts when the percentage of mark drops below a certain value, its contacts remaining open for all values of percentage of mark above that predetermined value and the contacts of relay 52 will be caused to close only when the percentage mark exceeds a certain predetermined value. For example, in a typical application the constants were adjusted so that relay 51 would close its contacts if the percentage mark became less than 25% for a period of over 10 seconds and the contacts of relay 52 would be closed if the percentage of mark exceeded 75% over a period of 10 seconds or more.

It is to be understood that variations in the constructional details of my invention may be made and that the two embodiments of the invention as illustrated in Figs. 1 and 2, respectively, are merely typical of devices of this character which are suitable for carrying out the stated primary object of the invention. The scope of the invention is, therefore, defined by the claims to follow.

I claim:

1. A monitoring system for telegraph circuits comprising a low frequency electron discharge

tube amplifier, responsive to "mark" and "space" signals, said amplifier including two collaterally disposed discharge tubes one of which is rendered conductive by an abnormal preponderance of marking signal time over spacing signal time and the other of which is rendered conductive by the abnormal preponderance of spacing signal time over marking signal time, means including a time constant circuit connected to said amplifier for integrating the time value of a succession of discrete mark signals received during a predetermined period, and means including an alarm signalling device responsive to the actuation of said collaterally disposed tubes for indicating aberrations of the integrated marking signal time from a predetermined normal percentage of said predetermined period.

2. A system in accordance with claim 1 and including two distinguishing indicators in said alarm signalling device, one being responsive to an excess of integrated marking signal time and the other responsive to a deficiency in the same.

3. A telegraph signal monitoring device comprising at least four electron discharge tubes in combination with two condenser-resistor delay circuit devices, three of said tubes being arranged in cascaded stages and the fourth tube being in a stage having an output circuit in parallel with the output circuit of the final tube of said cascaded stages, said fourth tube having an input circuit including a connection through one of said delay circuit devices to the output circuit of the first tube in said cascaded stages, the other of said delay circuit devices being in circuit between the second and third tubes of said cascaded stages, means including a differential relay having windings disposed respectively in the output circuits of the third and fourth tubes for producing separate responses to an unbalance between marking and spacing intervals of the signals to be monitored, and distinctive indicating means operable under control of said relay for producing indications of abnormal predominance of marking over spacing signals during a predetermined time interval in one instance and an opposite predominance during such a time interval in another instance.

4. In a receiving telegraph system having a plurality of electron discharge tubes disposed in a cascaded network, the method of indicating aberrations from a normal ratio between the integrated time values of marking signals with respect to spacing signals which comprises introducing a retardation effect in the control of one tube in the final stage of said network in response to variations in the conductivity of the tube in the preceding stage, whereby the tube in the final stage becomes conductive only when the ratio of marking to spacing signal time drops below a prescribed operating limit, introducing a retardation effect in the control of a collaterally disposed tube in the final stage of said network in response to variations in the conductivity of still another tube in a preceding stage, whereby this collaterally disposed tube in the final stage becomes conductive only when the ratio of marking-to-spacing signal time exceeds a prescribed operating limit, and causing indications to be made when either of the collaterally disposed tubes in said final stage becomes conductive.

5. In a receiving telegraph system having an arrangement of three electron discharge tubes in a cascaded network and a fourth tube in parallel with the tube in the final stage of said network,

each of said tubes being controllable by grid bias variations, said fourth tube being controlled directly by the output energy from the tube in the first stage of said network, the method of indicating aberrations from a normal ratio between marking and spacing signals which comprises introducing retardation effects in the control of the tube in the final stage and also in the control of said fourth tube, rendering the tube in the first stage conductive only in response to spacing signals, adjusting the control bias on the tubes of said cascaded network so that the tube in the final stage is rendered conductive only when the ratio of marking to spacing signals falls below a prescribed operating limit, adjusting the bias on said fourth tube so that it is rendered conductive only when said ratio exceeds another prescribed operating limit, and producing an alarm signal which is distinctive in respect to the particular tube thus rendered conductive in response to the retardation effect.

6. The method as set forth in claim 5 and including the further step of rendering said alarm signal intermittent.

7. A monitoring system for a telegraph circuit, comprising an electron discharge tube amplifier responsive to "mark" and "space" signals, means including time-constant circuits connected between stages of said amplifier for rapidly accumulating energy charges in proportion to the marking signal time and for slowly dissipating such charges in proportion to the spacing signal time, said means being capable of integrating said charges during a period which covers the reception of a succession of discrete marking impulses, said amplifier including two collaterally disposed discharge tubes one of which is rendered conductive by an abnormal preponderance of

marking signal time over spacing signal time and the other of which is rendered conductive by an abnormal preponderance of spacing signal time over marking signal time, said collaterally disposed electron discharge tubes having input circuits whose control bias is maintained below cut-off by an accumulation of energy charges in said time constant circuit under conditions of normal traffic code signaling.

10 8. A system in accordance with claim 7 and including an alarm device operable in response to current flowing through either of said discharge tubes.

15 9. A system for monitoring keyed telegraph signals comprising a first discharge tube having an input circuit and an output circuit, a time constant device in said input circuit, a second discharge tube under control of voltage variations in the output circuit of said first discharge tube, a third and a fourth discharge tube each

20 having a separate input circuit characterized by the inclusion of a time constant device, the third tube being controlled by output voltages from said second discharge tube, the fourth tube being controlled by output voltages from said first discharge tube, a three-position relay having opposing windings, one of said windings being connected in an output circuit of said third tube, the other of said windings being connected in an out-

25 put circuit of said fourth tube, and means responsive to the actuation of said relay for indicating departures in one direction and in the opposite direction from a normal ratio between the integrated time intervals representing marking and spacing pulses respectively of a telegraph message whose marking impulses are impressed on the input circuit of said first discharge tube.
